ATTY.

UNITED STATES PATENT OFFICE.

HUGH G. ROBINSON, OF OAKLAND, CALIFORNIA.

CUSHION HEEL-PLATE.

1,172,392.

Specification of Letters Patent. Patented Feb. 22, 1916.

Application filed September 23, 1915. Serial No. 52,205.

To all whom it may concern:

Be it known that I, HUGH G. ROBINSON, a citizen of the United States, residing at Oakland, in the county of Alameda and State of California have invented new and useful Improvements in Cushion Heel-Plates, of which the following is a specification.

The present invention relates to detachable wear plates for the heels of boots and shoes, adapted to be applied to the surface thereof at which the wear is greatest in order to equalize the wear on the heel.

The objects of the invention are to provide a wear plate that can be used to build up the worn-off rear surface of a heel without the necessity of much cutting with a knife or other sharp instrument; of a form convenient to receive securing nails or the like; having great wear-resisting properties and at the same time having a cushion effect; and that can be quickly and firmly secured in place and readily removed when worn to be replaced by a new one.

In the accompanying drawing, Figure 1 is a rear perspective view of a heel of a shoe showing my improved wear plate attached thereto; Fig. 2 is a similar view showing the under side of the wear plate; Fig. 3 is a sectional view thereof; Fig. 4 is a rear perspective view of an insert detached; Fig. 5 is a perspective sectional view of a modified form of insert.

Referring to the drawing, 1 indicates a wear plate of soft rubber molded so that its lower surface is flat and its upper surface is concave to fit snugly against the under side of the worn out rear surface of a shoe heel 2, thereby avoiding the necessity of cutting off layers of leather in order to obtain the proper fit of the wear plate to the heel. Said wear plate 1 is necessarily made considerably thicker at the rear than at the front, and, in fact, it tapers down almost to an edge at the front portion.

In the lower or flat side of the soft rubber wear plate is an approximately semi-circular groove 3, extending at a uniform small distance from the rear rounded edge of the wear plate and of uniform width throughout. The groove, however, varies greatly in depth at different parts, being comparatively deep at the middle or rearmost portion and diminishing gradually to nothing at each end. A grooved metallic insert 4 is embedded in the groove 3 in the rubber wear

plate. This insert consists of a curved grooved or channel-shaped piece of sheet metal of substantially the same form as the groove in the rubber, the two walls of the insert extending at a uniform distance from each other along their whole length, and the free edges of the walls being directed downward and being substantially flush with the lower face of the rubber wear plate. The metallic insert 4 is caused to adhere to the rubber wear plate by vulcanizing the rubber on the insert after the insert has been placed in position therein, and in order to further insure the adhesion of the rubber to the metallic insert, the rear or outer wall of the insert is formed upon its rear surface with vertical grooves 5 spaced apart a short distance. The rubber filling these grooves insures a firm adhesion of the rubber wear plate to the metallic insert. The free edges of the walls of the insert are roughened or corrugated, as shown at 6, to prevent slipping.

In the form of the invention shown in Figs. 1-4 the groove in the insert is rectangular in cross section, and in that shown in Fig. 5 it is rounded. In applying the rubber wear plate to the heel of a shoe, shoe nails 7 or equivalents thereof are driven through holes 8 in the bottom of the channel of the metallic insert and through the rubber wear plate into the heel of the shoe.

A metal insert is very durable and makes no rasping noise, this being prevented by the rubber which acts as a cushion.

By forming the insert with an apertured groove continuous along its whole length, provision is made for the heads of nails and driving of the nails into the heel is facilitated. At the same time the metal insert is more easily embedded in the rubber, for it is attached to prongs which depend from a suitable holder and which hold the insert firmly in place while the rubber is molded around the same, thus preventing it from being embedded in the wrong place.

The advantages of the invention will readily be seen from the foregoing description.

I claim:-

1. A soft rubber heel plate tapering toward each end and inward and having embedded and vulcanized therein close to the outer edge an approximately semi-circular metallic insert having front and rear continuous walls and a groove between said walls, each wall being tapered to both ends

which terminate in the front edge of the wear plate.

2. A soft rubber heel plate tapering toward each end and inward and having embedded and vulcanized therein an approximately semi-circular metallic insert having front and rear continuous walls and a groove between said walls, the rear wall being formed with recesses in its rear surface to firmly secure it to the rubber, the face of said walls being roughened or corrugated to prevent slipping and each wall being tapered to both ends which terminate in the front edge of the wear plate.

3. A soft rubber heel plate having a concave upper surface that permits it to fit snugly against the worn off rear surface of the shoe heel, and a rounded rear side to correspond with the shape of the heel taper-

ing toward each end and inward and having embedded and vulcanized therein an approximately semi-circular metallic insert having front and rear continuous walls and a groove between said walls, the rear wall being formed with recesses in its rear surface to firmly secure it to the rubber, the face of said walls being roughened or corrugated to prevent slipping and each wall being tapered to both ends which terminate in the front edge of the wear plate.

In testimony whereof I have hereunto set my hand in the presence of two subscribing witnesses.

HUGH G. ROBINSON.
